ART-STYLE FASTENER FOR PIN-UP
DRAWINGSWinfield A. Worth, Jr., Hyattsville, Md., assignor
of one-half to Jeanie H. Worth, Hyattsville, Md.

Application September 13, 1950, Serial No. 184,645

4 Claims. (Cl. 40—20)

1

The present invention relates to unique ways and means whereby attractive pin-ups, such as drawings, photographs and the like, may be cleverly and skillfully displayed from a room wall, from an artist's display board or the like.

It is a matter of common knowledge that unframed and unmounted sheets of drawings and relatively flimsy pictures and the like, especially those in the so-called pin-up category are often used to advantage in interior wall decorating requirements. Thumbtacks and in some instances special two-part fasteners are employed to clip or otherwise attach the drawing to a piece of tapestry or textile valance or panel and these for the most part have been accepted and used. There has, however, long existed a need for a differently constructed fastener for the purposes stated which is not only reliably useful and easy to handle but is, more importantly, characterized by eye appeal and other decorative properties which are calculated to appeal to and appease those concerned with interior wall decorating achievements. The instant invention, therefore, has to do with a unique and skillfully clever fastener which constitutes a novel contribution to the art and in which manufacturers and users will find their anticipated needs fully met, contained and amply available.

It is a further object of the invention to provide a simple and economical fastener construction for pin-up drawings and photographs which will adorn the over-all display with requisite nicety and which, because of its subtle prominence will appeal to users having a knack for dressing a wall surface with discretionary resultfulness.

Briefly summarized, the inventive concept has to do with the complete ensemble involving the fixed wall, a piece of tapestry or the like hung from said wall, a relatively small base member interposed and concealed between the wall and the reverse side of said tapestry, a fine sharp-pointed brad carried by said base member and projecting therefrom on an oblique angle, the pointed end of said brad piercing and passing beyond the obverse side of said tapestry, a sheet of drawings superimposed against said tapestry, and also pierced by said brad, and a dummy spike having a shank with an end-contacting said sheet, said brad being driven axially into said shank, whereby to bind the tapestry and sheet between the base member and shank.

Then too, novelty is predicated on that aspect of the situation wherein the so-called spike is of soft wood and easy to receive the pointed shank

2

of the brad, the end of the shank of the "spike" being obliquely mitered so as to bear against the picture and to give the observer the illusion that the shank of said spike actually pierces the sheet of drawings and tapestry and is "nailed" to said wall when, as a matter of fact, only the small brad passes through the tapestry and picture.

Other objects and advantages will become more readily apparent from the following description and the accompanying illustrative drawings.

In the accompanying sheet of drawings, wherein like numerals are employed to designate like parts throughout the views:

Figure 1 is a face elevational view showing a piece of tapestry or the like, the unmounted relatively flimsy artist's drawing and the improved fasteners and manner in which they are used to hang up the picture;

Figure 2 is a perspective view of the spike member of the fastener construction;

Figure 3 is a perspective view of the complementary brad equipped member; and,

Figure 4 is an exaggerated fragmentary sectional view showing the complete ensemble and manner in which the components combine.

Referring now to the views of the drawings by way of reference numerals and accompanying lead lines, attention is first directed to Figure 4 wherein A designates a fixed support such as a wall having hung or otherwise suspended thereon a fabric panel or the like B. This may, perhaps, be best visualized as, let us say, a piece of tapestry or, the other extreme, a piece of burlap. The unframed or so-called unmounted picture, photograph, drawing or the like, is denoted at C. This may be a simple flimsy sheet of drawing paper with an artist's sketch or the like D appearing thereon. There are four fasteners employed and these are, of course, secured to the corner portions of the drawing to thus attach it to and suspend it from the piece of tapestry B. Since each fastening device or construction is the same a description of one will suffice for all. Reference is therefore further had to Figure 4 wherein one unit or part of the fastener is denoted by the numeral 6. This is best shown in Figure 3 wherein it takes the form of a wooden or equivalent block 8 having flat surfaces and having a sharp-pointed wire nail or brad 10 driven therethrough. The brad takes an oblique position in respect to the coacting surface 12 of the block. This should be at an angle other than a right angle to obtain the desired artistic effects. The other unit or part of the fastener construction is denoted by the numeral 14 and this comprises a dummy

"spike" of prominence in size which might, perhaps, be referred to as oversize in proportions. This is preferably of wood and comprises a suitably finished tapering shank 16 having a knob-like head 18 at one end. The opposite end of the shank is mitered as at 20 and provides an abutment which is adapted to rest against the surface of the picture in the manner shown in Figure 4 to cant the spike at the approximate angle disclosed. The pointed shank of the brad passes through the tapestry, the picture, and is axially driven into the shank 16. Thus, the units 6 and 14 are nailed together and bind the tapestry and picture therebetween in horizontally secure fashion but also achieves an ornamental result in that the over-all ensemble is thus suspended as well as adorned. The use of the spike provides significant but subtle prominence and affords the user the decorative properties wanted. It is believed that the invention is a clever manifestation of that which is calculated to appeal to and appease those concerned with unique interior wall decoration accomplishments. It is, of course, important to stress the fact that the small or slender brad does not in any manner tear or disrupt the displayed pin-up or other item. On the other hand, it gives the observer the clever illusion that the spike has been actually driven through the picture, through the tapestry and into the wall, bringing about, as is obvious, a unique result indeed.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. In combination, a fixed wall, a piece of tapestry or the like hung from said wall, a relatively small base member interposed and concealed between the wall and the reverse side of said tapestry, a fine sharp-pointed brad carried by said base

member and projecting therefrom on an oblique angle, the pointed end of said brad piercing and passing beyond the obverse side of said tapestry, a sheet of drawings superimposed against said tapestry and also pierced by said brad, and a dummy spike having a shank with an end-contacting said sheet, said brad being driven axially into said shank, whereby to bind the tapestry and sheet between the base member and shank.

2. The structure defined in claim 1, said spike being proportionately exaggerated in size relative to said brad and the drawings on said sheet, being of soft wood and giving the observer the illusion that the shank of said spike actually pierces the sheet of drawings and tapestry and is "nailed" to said wall.

3. The structure set forth in claim 2, wherein said spike is also ornate and decorative and, being thus unique in appearance, functions to fancifully adorn the over-all ensemble.

4. As a new article of manufacture, a fastener for hanging an unmounted flimsy picture or sheet of drawings from a wall, tapestry, valance or the like, comprising a relatively small wooden flat surfaced block adapted to occupy a hidden position between a stationary wall or the like and said tapestry, a fine pointed relatively short brad driven through the center of said block and having the desired obliquity in respect to a surface of the block, and a relatively large knob, the latter being of wood, having a tapering shank with an ornamental head at its outer end, the opposite inner end of said shank being mitered to provide an oblique abutment, whereby when said brad is forced axially into said shank, the latter and brad project at an angle, other than right angles, relative to said block.
